UNITED STATES PATENT OFFICE.

WILLIAM LOUDEN, OF FAIRFIELD, IOWA.

CATTLE STANCHION.

Application filed October 11, 1924. Serial No. 743,009.

To all whom it may concern:

Be it known that I, WILLIAM LOUDEN, a citizen of the United States, residing at Fairfield, in the county of Jefferson and 5 State of Iowa, have invented a new and useful Improvement in Cattle Stanchions, of which the following is a specification.

My invention relates to stanchions comprising two side members hinged together 10 at their lower ends and adapted to be latched together and unlatched from each other at their upper ends, the stanchions being arranged to be hung in a stall frame; and it consists of an improvement in the 15 method of attaching supporting means to the upper ends of the members which are opened to admit the head of the animal, and closed to hold the animal in the stanchion, whereby the connections will be more se- 20 cure, and the opening and closing members will be duly supported and will be automatically held in their proper position when open, and may be turned freely to either side when closed. Also, of other features set 25 forth in the specification and claims.

In the accompanying drawing, forming a part of this specification, Fig. 1 is a side view of a stall frame having three stanchions embodying my invention hung there- 30 in, and each of the stanchions being shown in a different position to illustrate the operation of my invention. Fig. 2 is an enlarged vertically disposed longitudinal section on line 2—2 of Fig. 1. Fig. 3 is a 35 transverse section on line 3—3 of Fig. 2, the cut away portion of the figure being replaced to make it complete. Fig. 4 is a detail view. Fig. 5 is an enlarged perspective of a modified form of the invention 40 showing a portion of the upper end of the opening and closing member. Fig. 6 is a transverse section on line 6—6 of Fig. 5.

Referring to the drawings, A represents the manger curb of the stall frame, B, the 45 stall posts mounted thereon and C, the top rail of the frame secured to the upper ends of the stall posts. Stanchions having side members D and D' hinged together at their lower ends and adapted to be latched to- 50 gether and unlatched from each other at their upper ends, are mounted in the stall frame by chains E and E', or other equivalent fastening means, connecting the stanchions to the top rail above and the manger curb below in the usual manner. The upper 55 fastenings E are connected to the upper ends

of the members D which are also provided with latching means adapted to catch over latching spurs F on the upper ends of the members D' which is most plainly shown 60 in Fig. 2. The stanchion in the central portion of the stall frame is shown in the unlatched or open position and the stanchion at the ends of the frame are shown in the latched or closed position. 65

To prevent the members D' from swinging out too far when open, and straining the hinges and possibly breaking them, I use supporting chains G. The upper ends of these chains are connected to the top rail 70 C, preferably by adjustable clips H, located on the rail a short distance from the connections I for the fastenings E. When tubular side members are used, the lower ends of these chains are secured to the upper 75 ends of the members D' as follows. The latch spur F is provided with a cylindrical body J and a recess L is formed in the upper side of said body, as most plainly shown in Fig. 4, which is an enlarged perspective of 80 the spur and its body. The body J is inserted in the upper end of the member D' and is held therein by a bolt or rivet K. A corresponding recess is formed in the upper end of the member D' and the lower 85 link of the chain G is placed in the recess thus formed before the bolt or rivet K is inserted. The bolt or rivet being passed through the link as shown in Figs. 2 and 3, will securely hold the chain G to the mem- 90 ber D'. 95

By this means the members D' will not only be held from swinging out too far but will also be automatically held in alignment with the stall frame when open, as 100 shown by the central stanchion in Fig. 1. By this means the stanchion will be automatically held from turning at right angles to the frame when open, and thereby preventing the animal from placing its head in the open stanchion, as stanchions without this support are liable to do. In addition, to this, the chain being connected to the member D at a certain place near the central upper end of the stanchion will be 105 slack when the stanchion is closed, whereby it will be free to be turned around at right angles to the stall frame, and even more than right angles, as shown by the stanchion at the right hand end of Fig. 1. 110 The stanchion will also be free to turn as far in the opposite direction and the animal

will always be free to turn its head back against its side in either direction without any resistance whatever on the part of the stanchion.

5. It is preferable that tubular material be used for the side members of the stanchions, but if other forms are used, the body of the latch spur will have to be modified to suit the shape of the material used. Fig. 10 is a perspective of a portion of the upper end of a stanchion side member M, made in the form of an inverted T bar and having a latch spur F' attached thereto by means of a bolt or rivet K'. It will be seen that 15 the body N of the latch spur is made to embrace and fit the end of the T bar and that the central portion N' of the body is extended out on one side to form a recess between it and the web of the T bar for 20 the insertion of the lower link of the supporting chain G' which is securely held therein by the bolt or rivet K'.

When other different forms of side members are used, such as angles or U bars, the 25 body of the latch spur will have to be made to fit the contour of the material used, but the supporting chain should always have a connection with the body of the spur and preferably be held in place by the bolt or 30 rivet connecting the body of the spur to the side member. When so constructed and arranged no additional attaching means are required to connect the supporting chain to the side member and its connection there- 35 with will be most direct and positive. The construction is extremely simple and inexpensive to manufacture, as well as durable and efficient in operation.

What I claim is—

40 1. In cattle stanchions having side members hinged together at their lower ends and adapted to be latched together and unlatched from each other at their upper ends; one of said members having latching means 45 at its upper end, and being adapted to be connected to an upper portion of a stall frame, and the other member being provided with a co-operating latch spur having a body connected to the upper end of the member; and a flexible supporting device having its upper end connected to an adjacent upper portion of the stall frame and its lower end connected to the body of the latch spur.

55 2. In cattle stanchions having side members hinged together at their lower ends and adapted to be latched together and unlatched from each other at their upper ends; one of said members having latching means 60 at their upper end, and being adapted to be connected to an upper portion of a stall

frame, and the other member being provided with a co-operating latch spur having a body connected to the upper end of the member by a bolt or rivet; and a supporting 65 chain having its upper end connected to an adjacent upper portion of the stall frame and its lower end connected to the body of the latch spur by said bolt or rivet.

3. In cattle stanchions having tubular 70 side members hinged together at their lower ends and adapted to be latched together and unlatched from each other at their upper ends; one of said members having latching means at its upper end, and being adapted 75 to be connected to an upper portion of a stall frame, and the other member being provided with a co-operating latch spur having a cylindrical body inserted in the upper end of the member; a recess formed 80 in the upper side of the member and the body of the spur, and a supporting chain having its upper end connected to an adjacent upper portion of the stall frame, and its lower end inserted in the aforesaid re- 85 cess and fastened therein.

4. In cattle stanchions having tubular 90 side members hinged together at their lower ends and adapted to be latched together and unlatched from each other at their 95 upper ends; one of said members having latching means at its upper end, and being adapted to be connected to an upper portion of a stall frame, and the other member being provided with a co-operating latch spur having a cylindrical body inserted in the upper end of the member and secured therein by a bolt or rivet; a recess formed in the upper side of the member and the body of the spur, and a supporting chain 100 having its upper end connected to an adjacent portion of the stall frame, and its lower link inserted in the recess and held therein by the aforesaid bolt or rivet.

5. In cattle stanchions having side mem- 105 bers hinged together at their lower ends and adapted to be latched together and unlatched from each other at their upper ends, a stall frame having a top rail mounted on stall posts, one of the stanchion members 110 having latching means at its upper end and being connected to the top rail of the stall frame, and the other member being provided with a co-operating latch spur having a body connected to the upper end of the 115 member; and a flexible supporting device connected to a clip adjustable on the top rail, and its lower end connected to the body of the latch spur.

Fairfield, Iowa, October 9th, 1924.

WILLIAM LOUDEN.
